UNITED STATES PATENT OFFICE.

ARTHUR KITSON, OF PHILADELPHIA, PENNSYLVANIA.

APPARATUS FOR MANUFACTURING HEATING OR FUEL GAS.

SPECIFICATION forming part of Letters Patent No. 440,950, dated November 18, 1890.

Application filed December 27, 1889. Serial No. 336,109. (No model.)

To all whom it may concern:

Be it known that I, ARTHUR KITSON, a subject of the Queen of Great Britain, residing at Philadelphia, in the county of Philadelphia and State of Pennsylvania, have invented certain new and useful Improvements in Apparatus for Manufacturing Heating or Fuel Gas; and I do hereby declare the following to be a full, clear, and exact description of the invention, such as will enable others skilled in the art to which it appertains to make and use the same.

This invention relates to certain improvements in the method and apparatus for generating heating or fuel gas. These improvements consist, mainly, in features of construction, arrangement, and operation as follows: first, the internal shape and construction of the furnace, together with a movable fire-box having means for giving it both a rotary motion and an up-and-down vertical motion for shaking up the fuel and for preventing caking of the coal when bituminous or soft coal is used, and for removing ashes, cinders, &c.; second, the peculiar mechanism and method for raising and lowering the fire-box and at the same time giving it a rotary motion; third, a new and improved form of ash-box and means for dumping the ashes in connection with the ash-pit, so that ashes, cinders, &c., may be removed from the furnace without stopping the operation of manufacturing gas; fourth, a peculiar arrangement of steam generating and superheating coils provided at both the top and bottom of the generator, whereby water may be instantly converted into steam and the steam superheated before being supplied to the fuel in the generator; fifth, improved means for heating or superheating the combined mixture of steam and air which is supplied to the generator; sixth, a double cover for the top of the generator, provided with winding or circuitous channels for heating air or steam, or a mixture of steam and air, to be supplied to the generator, or for other purposes; seventh, an improved form of hopper and means for operating the same, by which labor is saved in supplying and replenishing fuel to the furnace; eighth, a peculiar form of stirrer or poker and mechanism for operating it for stirring up the fuel in the

generator, and, ninth, the general details of construction and operation of the generator by which it is adapted especially for burning bituminous or soft coal for the generation of 55 gas.

I will now describe in detail the construction and operation of my generator by reference to the accompanying drawings, in which—

Figure 1 represents a vertical section of the generator. Fig. 2 represents a plan view of the under side of the top plate of the furnace, showing the flanges and channels formed on such plate. Fig. 3 represents a top plan view of the base of the furnace containing the fire-box and ash-chamber. Fig. 4 represents a vertical section through the top of the furnace, the fuel-hopper, and the stirring mechanism. Fig. 5 represents a vertical section 65 of the top of the furnace with modified mechanism for operating the hopper-valves and stirring-rod. Fig. 6 represents a sectional 70 detailed view of means for operating the valves of the fuel-hopper. Fig. 7 represents 75 a top plan view of a special fuel-supporting bar arranged and operated at the top of the fire-box.

Like letters and numerals of reference indicate the same parts in the different figures of 80 the drawings.

The ash-chamber A, containing the fire-box B, is supported by the annular top plate P upon the columns Y', and the top of the furnace F rests upon the plate P. The ash-chamber is provided at the bottom with a downwardly-extending passage or opening a', having fitted in it a butterfly-valve a for the removal of ashes.

The top plate P is provided centrally with 90 a downwardly-extending annular flange p for receiving the fire-box and with downwardly-extending hangers II, provided at their lower ends with rollers h.

The fire-box B is provided near its bottom 95 with inner annular flanges b, supporting the brick lining, and is also provided on its outer surface with spiral flanges or tramways b' for supporting the box upon the rollers h. The fire-box is also provided near its bottom with 100 an outer toothed gear or ring B' for engaging with the pinion T, mounted on shaft t, by

means of which the fire-box is rotated and raised or lowered. The shaft t is journaled at top and bottom and has secured to it the bevel gear-wheel z' , meshing with the bevel-gear z , secured to the inner end of horizontal shaft Z , which is provided at its outer end with handle Y . By means of this mechanism the fire-box is readily rotated and raised or lowered, according to the direction in which the handle is turned. The object of these two motions is to shake up the fuel more thoroughly and to provide for more effectively using bituminous or soft coal in the generator. Slots or narrow passages b'' are provided in the upper portion of the fire-box for admission of air all around its circumference when it is lowered below the flange p . Near the bottom of the fire-box and below its inner flange b is arranged a rocking and dumping grate W , the parts of which are secured to horizontal shafts extending through the walls of the furnace, where they are provided in practice with levers for operating them. The shaft may also be provided with gears meshing into each other, so that when one shaft is turned the other will be simultaneously turned for raising or lowering the interlocking portions of the grate for shaking out the ashes or for dumping it when desired into the ash-chamber. In practice four hangers, each provided with a roller, are used for supporting the fire-box by its spiral flange b' . The brick lining of the fire-box is preferably inclined downward and inward, so as to extend and increase the heating-surface, and also to contract the grate-opening. The upper portion of the furnace is composed of fire-brick and an outer iron jacket, the brick lining being inclined inward and upward from the annular plate P up to the top. The upper portion of the fire-box B is made of greater diameter than the bottom of the furnace F . The object of this is to prevent caking when soft coal is used and to keep the fuel more compact. Thus when the box B is lowered the entire weight of the fuel exerts its full pressure downward unchecked by the friction of the side walls of the furnace, as when such walls extend upward from top to bottom or are inclined inward toward the grate, as in most furnaces. Any bridge or arch formed in the upper portion of the fuel is readily poked down by means of the poker L , as shown in Figs. 1, 4, and 5. Passages E are provided in the walls of the furnace near the base of the fuel-chamber, and in such passages are placed the sharp supporting-bars D , having handles d , as shown in Figs. 1 and 7. Bar D is made of wrought-iron and is pointed at the end in order to readily cut through the fuel. The object of this bar is mainly to support the large body of fuel when the ashes and cinders are dumped out of the fire-box B . It serves also to break up the fuel, clinkers, &c. The handle d of the bar works through a stuffing-box e at the end of casing E . A number of these bars may be arranged at dif-

ferent points around the base of the generator for better supporting the fuel. Instead of providing the stuffing-box E with a casing, the bar may be withdrawn and the passage-way closed with a plug or cap.

When the box B is clogged or filled with ashes or clinkers, one or more of the supporting-bars D are placed across the bottom of the furnace and the grate is opened, when the entire contents of box B are dumped into the ash-chamber A . The grate is then closed and the bar or bars D withdrawn, when the body of fuel in chamber F falls to a depth corresponding to the capacity of box B . A charge of fuel is immediately let into the top of the furnace through the hopper G , Figs. 1 and 4. It will be seen that the new fuel falls at once into the space previously occupied by the incandescent fuel and becomes gasified by the heat contained in the brick-work. In some cases, to avoid caking of coal, a fresh charge of fuel may be mixed at once with the incandescent fuel by introducing it before taking out the supporting-bar D . A new charge falls with the whole body of the fuel and becomes mixed with it. A similar effect may be produced by lowering the fire-box B by turning handle Y and the intermediate gearing (after first having introduced a fresh charge of coal) and then raising it again. The fuel becomes thoroughly mixed and forms a compact body, especially if stirred at the same time with the stirring-rod or poker L . In making gas where a new charge of fuel is introduced, I inject steam, or steam and air mixed, from below at the port V'' and take the resulting gas off at the middle portion of the furnace through pipe O , located below the top of the fuel at a point where the fuel is incandescent. The gases generated from the new charge of fuel are thus caused to pass down through a portion of the hot fuel, thereby becoming fixed, and they pass off with the gases resulting from the decomposed steam.

The steam-generating coils Q are formed at the base of fuel-chamber F , preferably in the brick wall, as shown, and one end of the pipe extends out through the wall of the furnace and has connecting with it the small water-supply pipe J , leading from the city water-main or an elevated tank or from a pump, so that water may be forced under pressure and in the form of a spray into the coil-pipe. A vertical pipe q connects the coil Q with a larger coil Q' , arranged at the top of the generating-furnace and across the outlet-flue for the escaping gas. The coils Q' are made larger in size than those at the base to afford room for the expansion of the steam, also to produce dry steam and a large supply thereof. The pressure is thus made more uniform. A smaller pipe Q'' leads from coils Q' to the Körting blower Q''' or other similar steam and air injector, located at the top of the furnace and above the outlet-flue, where the heat is the greatest. The steam-coils are

arranged so that the cold water is introduced in the form of a spray into the coolest portion of the pipe and so that the water or resulting vapor ascends gradually to the hottest 5 part of the pipe above, where it is converted into superheated steam. The top of the furnace is made double and is composed of the flat plate *f* and the plate *C*, provided with downwardly-extending flanges arranged 10 to form a circuitous passage or channel, as shown in Fig. 2. The channels transformed in the double top of the furnace conduct the steam and air over the hottest part of the furnace, whereby they are superheated before 15 being injected into the body of the fuel. This arrangement of the superheater at the top of the furnace is quite advantageous, as by means of it much heat is saved and utilized. Passage-ways *R R* are also made in the lining of 20 the furnace for conducting steam or a mixture of steam and air down to the ports *V' V''*, from which they escape into the fuel. One of the passages *R* leads down to the base of chamber *F* and connects with the superheating-coils *r* just above the plate *P*, and the port *V''* leads from such coils *R* into the fuel-chamber. 25 The passages *R R* and the passage *V* connect with the superheating-channels in the double top of the furnace, and such passages are controlled by screw plugs or valves 1, 2, and 3, 30 passing through the top plate *C*. Pipes *w w'*, provided with the valves 7 and 8, conduct steam from pipe *Q''* through the valve-plugs 1 and 2 into passages *R* and *V*. A third steam-pipe leads to valve-plug 3 for conducting steam through passages *R* and port *V'* below the top of the fuel. The pipe *u*, provided with a valve, connects with valve 7 for supplying hydrocarbon oil through valve 1 and passage 35 *V* into the top of the furnace. The steam and oil may be passed together through valve 7 and its connecting-pipe. The screw-plugs 1, 2, and 3 are provided with seats on plate *f* in the double top of the furnace, as shown at 40 valve *I*, so that steam or mixed steam and air may be shut off from any one of the passages *R* or *V*. By means of the supply-pipes and valves 7 and 8 additional steam may be injected with a mixture of steam and air which 45 is heated in the channels of the double top of the furnace. Steam alone may be injected by closing the plugs 1, 2, and 3 and opening one or more of the steam-valves 7 or 8. The injectors are arranged to blast either up or down 50 through the fuel or near the central portion at *V'*, and gas may be taken off either at the outer exit *X* or near the center at *O* or at the bottom *X'*. The furnace may also be blasted either up or down at the same time and the 55 resulting gas taken off at *O*. By means of the bottom coils *Q* and top coils *Q'* steam is readily generated on first lighting the fire and can be used in a very short time in the injectors for creating an air-blast. 60

65 The hopper *G* passes centrally through the top plate *C* and opens into the top of the furnace. It is provided at the bottom with a

conical valve *g*, as shown in Fig. 4, and is provided at a point above with a guideway *s*, into which is fitted a slide *S*, sharpened at its lower edge for cutting through the fuel. The slide *S* is pivotally connected to the under side of the weighted lever, composed of a trough or case *I*, which is pivoted to a standard *j*, as shown in Fig. 6. The trough *I* contains a heavy cast-iron ball *i*, which rolls freely from one end to the other of such trough as it is tilted on its fulcrum. This trough-lever is connected by a strong cross-bar *k* with the lever of sleeve-rod *g'*, connecting with a conical valve *g*, so that the cutting-slide *S* and valve *g* may be operated simultaneously for supplying a fixed charge of fuel to the generator. The trough-lever *I* is arranged parallel with the lever for operating the hopper-valve *g*, so that the two levers are easily operated together. The stirring-rod or poker *L l* passes up through the sleeve-rod *g'*, and is provided at the top with a wheel *m* for turning it and with an eye, to which is connected a chain or rope *l' l'*, passing over the supporting-pulleys *n*, suitably supported in hangers above the generator. The poker is raised by the chain and is then allowed to fall by its own weight, thereby breaking up 95 the fuel. When it is inserted into the fuel, it may also be turned by the wheel for better stirring and breaking up any crust that may be formed in the coal. In Fig. 5 I have shown a lever *l''*, pivoted to a standard *n'*, for operating the poker *L*. I have also shown a weighted lever *k'*, pivoted to standard *j'*, for raising and lowering the hopper-valve *g*. These are modifications which can be readily applied and operated in place of the mechanism shown in Fig. 4.

An ash-pit *5* is arranged below the ash-chamber *A*, and may be made to closely surround the extension *a'''* of such chamber to receive the ashes discharged from the chamber by valve *a*, and thus prevent annoyance of dust and dirt escaping when the furnace is cleaned. The ash-pit *5* is made air-tight, and the ashes can be dumped in it while the generator is in operation without loss of gas. 110 An air and steam blast pipe may connect directly with the ash-chamber *A* below the top plate *P*, so as to supply air, or air and steam, up through the grate *W* or through the passage *b''* when the fire-box is sufficiently lowered. The winding-channel in the double top of the furnace may open directly through the outer circumferential wall of plate *C*, as shown in Fig. 2, or such wall may be closed and a passage-way or opening arranged in the top 120 of plate *C*, where the Körting injector *Q'''* connects, as shown in Fig. 1.

The furnace may be operated for the production of gas as follows: Valve 10 is opened, and valves 11, 12, and 13 are closed, and then valve *a'* in the ash-chamber is opened, and the fire is lighted in the furnace, and fuel is gradually supplied through the hopper till a brisk fire is started and steam is generated. As

soon as steam is generated in the coils valve a' is closed, and the blower Q'' is used for injecting air, in the first instance, through valve 2, pipe R, coil r , and port V'' . By this means the fire is blasted and soon heated to incandescence. Fresh fuel is supplied at suitable intervals until a deep body of it is formed in an incandescent condition. As soon as the furnace is full of fuel in a good condition for generating gas steam may be admitted through valve 8 in connection with the air-blast from the blower Q'' . Gas of a better quality and containing a larger per cent. of hydrogen and carbonic oxide is thus produced. So soon as gas of a good quality is being generated valve 10 is closed, valve 11 opened, and the gas as generated is conducted off to the place of consumption or to a holder. As occasion requires and when the fuel is in proper condition, air or steam and air mixed may be injected through the ports V V'' and the resulting gas taken off through the pipe X' , leading from the ash-pit or through the pipe O , leading from the middle portion of the furnace. Various kinds and qualities of gas may be made in my generator. For ordinary industrial purposes, brick-burning, &c., I use the steam-blower, together with as much more superheated steam as the fire will decompose without too great loss of heat. When gas is required for both heating and lighting purposes, I conduct the operation intermittently—that is, I first use the blower alone, making producer-gas and run it to a holder, at the same time heating the fuel to a high temperature or state of incandescence. Then I supply a fresh charge of fuel to the furnace and inject steam alone from below—that is, at port V'' —and a certain quantity of steam and oil from above through valve 7 and passage V. Water-gas composed of hydrogen and carbonic oxide is produced by the decomposition of steam passed up through the fuel from port V'' , and hydrocarbon or carbureted hydrogen is generated by the passage of the oil and steam downward through the fuel from port V, and these pass off through the pipe O and thence to a separate holder. The water-gas and the hydrocarbon gas readily mingle together in the pipes and in the holder, making an excellent quality of gas for both heating and lighting. By a careful observance of the condition of the fuel the oil may be injected at the top, vaporized in the fuel where it is at a comparatively low temperature, and the resulting vapor converted into fixed gas without producing lamp-black. The hydrocarbon oil is injected through the valve 7 by means of steam supplied through pipe w .

For the purpose of operating gas-engines I sometimes use the mixed water-gas and producer-gas, and sometimes mix with such gases a small amount of oil-vapor or carbureted hydrogen generated from a small supply of hydrocarbon oil. Thus I may inject the

steam and air through the port V'' below and at the same time inject steam, air, and oil from above and draw-off the resulting gas through the pipe O . By this method I obtain a more explosive gas than that produced by the simple mixture of water-gas and producer-gas. In such cases I inject steam and oil at the top of the generator and steam and air at the bottom and unite the resulting gas at pipe O .

By utilizing the radiant heat stored up in the brick-work and the generator-cover by means of air and steam passage-ways arranged as described, as well as the sensible heat of the escaping products, I am enabled to make a higher grade of water-gas and producer-gas than that usually manufactured. I secure a further advantage by use of the hot blast of air for the combustion of the gas itself after it is produced. In order to accomplish this I connect the superheating-coils located at the bottom of the furnace to the pipe leading to the place where the gases burn and there unite it with the gas. I may also use the heated air in gas-engines by connecting the air-valve of the engine to the coil of pipe r .

By placing the blower on top of the generator I keep it hot and avoid cooling the steam. The quantity of gas generated may be regulated by attaching the handle of the blower by chain and pulleys to the top of the gas-holder.

Having now particularly described and ascertained the nature of my said invention and in what manner the same is to be performed, I declare that what I claim is—

1. In a gas-generator, the fuel-chamber having its walls inclined downward and outward internally, in combination with a movable fire-box or grate which supports the entire weight of the body of fuel and mechanism for simultaneously giving such fire-box or grate both a rotary and an up-and-down motion, substantially as and for the purpose described.

2. In a gas-generator, the fuel-chamber having its walls inclined downward and outward internally, in combination with a movable fire-box having its walls inclined upward and outward and means for giving such fire-box an up-and-down motion for shaking up the fuel and mixing fresh coal with the coke in the fuel-chamber, also preventing caking of the coal, and for shaking out the ashes, as described.

3. In combination with the fuel-chamber of a gas-generator, the movable fire-box having inclined or spiral flanges and a toothed gear-ring, in combination with suitable supports for the flanges and suitable gear-wheels for rotating the fire-box and causing it to be raised and lowered, as and for the purpose described.

4. In combination with a gas-generator, a movable fire-box having openings formed in

- its walls and fitted within a downwardly-extending flange or ring γ and mechanism for raising and lowering such fire-box, for the purpose described.
5. In combination with a gas-generator, a movable fire-box having secured within it a dumping-grate and mechanism for giving such fire-box both a rotary and an up-and-down motion, as described.
10. 6. In combination with the furnace and the movable fire-box, an ash-chamber surrounding such box, having an inclined bottom provided with a downward extension and a tightly-closing valve for dumping the ashes into a connecting ash-pit, as described.
15. 7. In combination with a gas-generator, the movable fire-box, mechanism for giving such box a rotary and vertical motion, a dumping-grate, and the extra bars D, arranged in passages at the base of the fuel-chamber and above the fire-box, as and for the purpose described.
20. 8. In combination with a gas-generator, the heating-coils arranged near the bottom of the fuel-chamber and having means for supplying them with a jet or spray of water and the steam superheating-coils arranged at the top of the fuel-chamber and partly in the flue of the outgoing hot gas and connecting with said heating-coil, for the purpose described.
25. 9. In combination with the gas-generator, the double top of the furnace having vertical partitions forming winding passages and means, such as a steam-jet blower, for supplying the passages with air or a mixture of
30. 35. air and steam, and passage-ways leading from

the double top into the fuel-chamber of the furnace.

10. In combination with the double top of the furnace having winding or circuitous passages, an injector connecting therewith for supplying air and steam to be heated, passage-ways leading therefrom into the furnace, screw-plug valves for closing such passage-ways, and steam-supply pipes connecting with the passage-ways for supplying an additional quantity of steam to the mixture of steam and air which is supplied to the furnace from the double top, as described.

11. In combination with a gas-generator, a fuel-supply hopper having a conical valve at the bottom and a sharp-edged slide-valve above, an operating-lever connecting with the rods of both such valves and a bar connecting the levers, and means for simultaneously operating the two valves for supplying fuel to the furnace, as described.

12. In combination with the furnace and its fuel-hopper, a conical valve having a hollow rod, a connecting-lever for operating it, a stirring-rod or poker passing down through such hollow valve-rod, and means for raising, lowering, and turning the poker, for the purpose described.

In testimony whereof I affix my signature in presence of two witnesses.

ARTHUR KITSON.
